By Percy Atkinson
Attorney.

UNITED STATES PATENT OFFICE.

LILES H. LIGHTFOOT, OF SIGNAL MOUNTAIN, TENNESSEE, ASSIGNOR TO DU BOIS RUBBER & TUBE COMPANY, OF CHATTANOOGA, TENNESSEE.

DESIGN FOR A TIRE TREAD.

60,753.

Specification for Design.

Patented Apr. 4, 1922.

Application filed June 11, 1921. Serial No. 476,954. Term of patent 3½ years.

To all whom it may concern:

Be it known that I, LILES H. LIGHTFOOT, a citizen of the United States, residing at Signal Mountain, in the county of Hamilton and State of Tennessee, have invented a new, original, and ornamental Design for Tire Treads, of which the following is a specification, reference being had to the accompanying drawing, forming part thereof, in which—

Figure 1 is a front view of a tire showing my design and Figure 2 is a section on the line 2—2 of Figure 1.

I claim:

The ornamental design for a tire tread as shown.

LILES H. LIGHTFOOT.
